WORK-TABLE MECHANISMS FOR BLIND-STITCH MACHINES

Frank Parry, Trumbull, Conn., assignor to The Singer Manufacturing Company, Elizabeth, N. J., a corporation of New Jersey

Application June 7, 1952, Serial No. 292,264

12 Claims. (Cl. 112—260)

This invention relates to blind-stitch sewing machines and more particularly to an improvement in the supporting structure of the work-table, whereby the latter can be accurately raised and lowered to accommodate the machine to materials of different thicknesses, and also to position the work-table accurately with respect to the presser-foot and stitch-forming mechanism so that true blind stitches can be made with a minimum of stitch-exposure on the outer face of the material.

It is an object of the present invention to provide an improved work-table mechanism having provision for micrometer adjustment of the normal elevation of the work-table.

Another object of the invention is to provide a work-table elevation regulating means having a conveniently located manually operable adjusting element supported on a detachable cover, the removal of which will expose the regulating means for adjustment, repair or replacement.

Still another object of the invention is to provide a work-table elevation regulating means which is effective bodily to elevate the work-table relative to the presser-foot as opposed to pivotally elevating the work-table about a fixed axis as is common in previous machines.

With these and other objects in view, which will more fully appear, the nature of the invention will be more clearly understood by following the description, the appended claims, and the several views illustrated in the accompanying drawings.

In the drawings:

Fig. 1 is a top plan view of a machine constructed in accordance with my invention, the bed cover-plate being removed and certain of the parts being in section better to illustrate the details of the machine.

Fig. 2 represents a vertical sectional view taken substantially along the line 2—2, Fig. 1.

Fig. 3 represents an enlarged horizontal sectional view taken substantially along the line 3—3, Fig. 2, showing the adjustable stop for determining the normal elevated operating position of the work-table and a portion of the spring-biased linkage utilized for maintaining the work-table in contact with the adjustable stop.

Fig. 4 is a front elevational view of the sewing machine with the right hand portion of the work-table broken away and the bed and a portion of the standard in section to disclose the mechanism located within the standard.

Fig. 5 represents an enlarged transverse vertical sectional view taken substantially along the line 5—5, Fig. 1, showing the eccentric mounting of the work-table on the base of the machine.

Fig. 6 represents a vertical sectional view taken transversely of the work-table, showing a modification of the means employed for connecting the work-table to the yieldable work-table elevating means.

Fig. 7 represents a horizontal sectional view taken substantially along the line 7—7, Fig. 6.

2

Fig. 8 is a left hand elevation of the cable-securing clamp shown in Fig. 6.

Referring to the accompanying drawings, the improved sewing machine includes a frame comprising a base or base-arm 10 having a hollow standard 11 rising from the rear right hand corner thereof. Extending laterally towards the left from the upper end of the standard is a horizontal upper arm 12, and extending forwardly from the left hand end thereof is a frame-arm 13. Attached to the free end of the arm 13 is a stationary presser-plate or foot 14 against which the work is clamped by a pair of conventional vertically yieldable work-clamping members 15 carried by a work-table 16 which is supported by the base 10.

Journaled in the horizontal arm 12 is a main rotary shaft 17 which, through the usual connections disclosed for example in the U. S. patent of Dearborn, No. 705,325, July 22, 1902, oscillates a needle shaft 18 which is journaled in the forwardly extending arm 13. Carried by the forward end of the needle shaft 18 is a curved needle 19 which oscillates directly above the presser-plate 14 and in a path transverse to the longitudinal axis thereof, the forward or work-penetrating stroke being from left to right. Cooperating with the needle in the formation of chain-strokes is a looper 20 actuated, in the manner shown in the U. S. patent of Dearborn, No. 639,669, December 19, 1899, from the main shaft 17. The work is fed rearwardly past the needle 19 by means of a four-motion feed-dog 21 which operates through a hole in the presser-foot 14 and in opposition to the vertically yieldable work-clamping members 15, all in a manner substantially like that disclosed in the U. S. patent of Dearborn No. 1,592,446, July 13, 1926.

The work to be stitched is supported on the work-table 16 which is formed at its free left hand end as a tube or horn beneath the stitching and feeding mechanisms and at its right hand end is enlarged into substantially rectangular form having a convex upper surface, closed by a cover-plate 22 (Fig. 2), and a pair of depending end-walls 23 and 24. The end walls 23 and 24 are preferably fitted with bushings 25 and 26 (Fig. 5) in which are journaled the reduced eccentrically located opposite ends 27 and 28 of a work-table supporting shaft 29 freely journaled in the spaced upstanding lugs 30 and 31 integral with a bracket 32 detachably secured by screws 33 to the bed 10. Spring means is employed for yieldingly urging the work-table into its normal elevated work-presenting position determined by a stop-screw 34 which is threaded into the depending front wall 35 of the work-table 16, the stop-screw 34 at its inner end bearing against a stop-plate 36 secured by a screw 37 to an ear 38 cast on the bracket 32. Treadle or knee-shift controlled means is provided for pivotally lowering the work-table 16 about the eccentrically located ends 27 and 28 of the work-table supporting shaft 29. This means preferably includes a rock-shaft 39 (Figs. 1 and 5) journaled in a bracket 40 attached to the base 10, the rock-shaft 39 being bent to extend across the front of and downwardly beneath the machine to form a knee-shift arm 41 carrying adjacent its lower end a knee-pad 42. The rock-shaft 39 has secured to it a rock-arm 43 connected at its inner end by a wire-link 44 to the work-table 16. Pressure applied to the knee-pad 42 causes the work-table to tilt downwardly about its pivotal support, thus moving the tubular portion of the work-table away from the overlying presser-foot to release the work.

The spring means employed for yieldingly urging the work-table 16 into its elevated position is arranged so that, as the work-table is lowered by manual actuation of the knee-shift, the effort required by the operator becomes less as the work-table approaches its lowered position. To that end, the means shown in Figs. 1, 2 and 3 comprises a

link 45 connected at one end by a screw 46 to the depending wall 35 of the work-table 16 and at its other end connected by a screw 47 to one side of a pivotally mounted element or bell-crank lever 48 which is fulcrumed on the shouldered pivot-stud 49 threaded into the ear 39. To the other side of the bell-crank lever 48 there is attached, by a screw 50, one end of a link 51 having its other end connected to a rather heavy coil-spring 52 which is anchored to a stud 53 endwise adjustable in the machine-frame. The desired reduction in effort required as the work-table approaches its lowered position results from the fact that as the work-table is lowered there is a relative increase in the effective length of the lever-arm represented by the distance from the axis of the pivot-screw 49 to the axis of the screw 47 simultaneously with a decrease in the effective length of the lever-arm represented by the distance from the axis of the pivot-screw 49 to the axis of the screw 50. Stated more broadly, it may be said that the ratio of the effective lever-arm lengths increases in the work-table lowering action of the knee-shaft 42, resulting in a lessening or diminishing of the effort required by the operator. Figs. 6, 7 and 8 illustrate a modification of the means for connecting the coil-spring 52 to the work-table 16. In the modification, the bell-crank 48 together with the link 45 has substituted therefor a drum 54 turnably mounted on the shouldered stud 49 and about which there is wound a flexible cable 55 having one end secured to the drum 54 by the screw 56 and its other end attached to the depending front wall 35 of the work-table 16 by a securing screw 57 and a clamp-bar 58. It will be understood that with the parts in the position as shown in Fig. 6, manual lowering of the work-table 16 about its pivots 27 and 28 will cause the depending front wall 35 of the work-table to swing upwardly to the left and, through the cable 55, the drum 54 will turn in a clockwise direction causing the link 51 to move to the left in opposition to the coil-spring 52. When the work-table is released, the spring 52 causes the work-table to swing back to its normal elevated position determined by the stop-screw 34. The modification also has the advantage of requiring less effort as the work-table approaches its lowered position, this being the case by virtue of the fact that the effective lever-arm represented by distance of the center of the shouldered screw 49 to the center of the screw 50 decreases relative to the radius of the drum 54 as the work-table moves to lowered position.

The work-table 16 provides supporting means for the usual ridge-former 59 (Fig. 4) which functions in cooperation with the presser-foot 14 in forming a bight in the material facilitating the penetration of the material by the curved needle 19 so as to form blind stitches. In the machine illustrated, the ridge-former 59 is actuated so that shallow or skip stitches are formed between successive deep or anchor stitches. This is automatically accomplished by periodically raising and lowering the ridge-forming element or fin independently of the work-table. The mechanism disclosed in the drawings for effecting this rise and fall of the ridge-former forms the subject of another of my patent applications Serial No. 292,263, filed herewith and, therefore, reference may be had to that application for a complete disclosure of that mechanism. Suffice it to say that in the present drawings, the ridge-former 59 is illustrated as being clamped upon the left hand endportion of a tubular shaft 60 freely journaled to oscillate on the eccentrically disposed body of a telescopically arranged skip-stitch shaft 61 supported at its opposite ends in spaced bearings 62 provided within the work-table 16. At its right hand end, the tubular shaft has clamped on it a depending rock-lever 63 connected by a rearwardly extending link 64 to the depending arm 65 of a bell-crank lever freely fulcrumed on a skip-stitch pivot-stud 66 which is supported in the machine standard 11 vertically beneath and in parallelism with the rotary main-shaft 17 of the machine. The rearwardly extending horizontal arm 67

of the bell-crank lever is connected to the lower end of a pitman 68 whose upper end embraces an eccentric 69 fast on the main-shaft 17. Rotation of the main-shaft 17 will effect a complete oscillation of the ridge-forming element 59 during each stitch-forming cycle in a direction to assist the feed-dog 21 in advancing the material through the machine. The height of the ridge-forming element 59 is normally set by manually adjusting, by means later to be described, the elevation of the work-table 22 in accordance with the thickness of the material being sewn. When the ridge-former 59 is in the forward end of its oscillatory stroke, the work is properly positioned for penetration by the needle 19.

In order to form skip stitches between the anchor stitches, means is provided for turning, to a limited extent, the eccentric bodied skip-stitch shaft 61 within the tubular ridge-former supporting shaft 60. Turning of the skip-stitch shaft 61 relative to the tubular shaft 60 effects a bodily drop of the ridge-former 59 and its tubular shaft relative to the needle 19 so that the latter, in penetrating the work, passes through less than the total plies of material folded over the ridge-former 59. The means for turning or oscillating the skip-stitch shaft 61 comprises a rock-lever 70 clamped upon the right hand end of the skip-stitch shaft 61 and having its lower end connected by a rearwardly extending pitman 71 embracing an eccentric 72 which is secured on a belt driven sprocket 73 journaled on the skip-stitch pivot-spindle 66. The sprocket 73 is driven by a clip-belt 74 from a belt sprocket 75 on the arm-shaft 17, the ratio of the belt-sprockets 73 and 75 illustrated in the drawings being such that the main-shaft 17 makes two revolutions for each revolution of the skip-stitch eccentric 72. It will be apparent that the ratio between the main-shaft and the eccentric 72 on the skip-stitch pivot-spindle may also be of the order of 3-to-1 or 4-to-1.

Referring again to the work-table 16, means are provided for adjusting the height thereof to regulate the depth of penetration of the blind-stitch. This means, best shown in Fig. 2, is capable of micrometer adjustment and includes a manually controlled element, the actuation of which turns the work-table supporting shaft 29 which, owing to the eccentrically disposed ends 27 and 28 thereof, results in bodily elevating or lowering the work-table relative to the stitching mechanism. The manually controlled work-table height adjusting means comprises a rock-lever 76 clamped on the work-table supporting shaft 29 and having connected thereto one end of a rearwardly extending link 77 which is connected at its other end to the lower end of a vertically disposed adjusting lever 78 fulcrumed intermediate its ends on a pivot-stud 79 fixed in a lug 79' preferably cast integral with one wall of the machine-standard 11. At its upper end, the adjusting lever 78 is formed as a yoke 80 of which the parallel limbs are slotted, as at 81, to receive the side pins 82 of a block 83 which is threaded upon an adjusting screw 84. The adjusting screw 84 is formed with a cylindrical body-portion 85 rotatably disposed in an extended part 86 of a detachable cover-plate 87, the adjusting screw 84 being constrained against endwise movement in the cover-plate by a flange 88 and a thumb disk 89 secured by a screw 90 to the squared end 91 of the screw 84. Indicia scribed in the peripheral face of the thumb disk 89 facilitates the accurate adjustment of the normal elevated position of the work-table 16. From the above, it will be understood that manual turning of the thumb-disk 89 causes the block 83 to travel along the adjusting screw 84, whereby the connections 76, 77 and 78 are actuated to turn the work-table supporting shaft 29 in its bearings 30 and 31, causing the eccentrically disposed ends 27 and 28 of the work-table supporting shaft bodily to elevate or lower the work-table 16. It will be obvious that by journaling the adjusting screw 84 in the detachable cover-plate 87 and by forming the

upper end of the adjusting lever 78 as a yoke, the detachable cover-plate 87 can be readily removed from the machine and when so done all the mechanism within the standard 11 is conveniently accessible for replacement or adjustment. The bed 10 at the top is also closed by a cover-plate 92, the removal of which gives access to the mechanism within the bed. It will be appreciated that with the cover-plates 87 and 92 being located as shown in Fig. 2, they may be removed without having to drain all the oil from the bed 10. Moreover, it will be appreciated that the cover-plates 87 and 92 are constructed and arranged and are of such a size that all the mechanism within the base-arm 10 and standard 11 is exposed when the plates are removed. Also, in the initial assembly of the machine, or during adjustment or repair, with the cover-plates removed the machine may be operated, and the action of the mechanism within the base-arm and standard observed during its operation. While I have shown cover-plates 87 and 92 to be made separate, it will be obvious that a single L-shaped cover-plate could be utilized to close both the base 10 and standard 11.

To provide for increasing the work-supporting surface of the work-table 16 when the machine is to be used for flat work there is a swing-out plate 93 supported to swing about a vertical pivot 94 provided on an upwardly curved bracket 93 sustained by the machine-bed. A wing-nut 96 and stud 97 depending from the swing-out plate 93 and cooperating with an open-ended slot 98 in the bracket 95 provide locking means for fastening the swing-out plate in operating position in the horizontal plane of the top of the tubular work-table 16.

Having thus set forth the nature of the invention, what I claim herein is:

1. In a blind-stitch sewing machine, a main frame including a standard having an upper arm extending laterally therefrom and terminating in a forwardly extending frame-arm, and a base-arm section extending forwardly from said standard and cooperating with the latter to support the frame; a work-table section movably mounted on said base-arm and having a portion disposed at a level below the free end of said forwardly extending frame-arm; a work-table supporting shaft mounted in said work-table and journaled for limited turning movement on said base-arm and providing the support about which said work-table moves, said work-table supporting shaft having at least one eccentrically disposed portion with which one of said sections is in bearing contact; and work-table supporting shaft turning connections operatively associated with said work-table supporting shaft for effecting limited turning of said shaft to move said work-table section upwardly or downwardly relative to said frame-arm.

2. In a blind-stitch sewing machine, a main frame including a standard having an upper arm extending laterally therefrom and terminating in a forwardly extending frame-arm, and a base-arm extending forwardly from said standard and cooperating with the latter to support the frame; a work-table mounted on said base-arm and having a portion disposed below the level of the free end of said forwardly extending frame-arm; and means for mounting said work-table on said base-arm including a work-table supporting shaft mounted for limited turning movement on said base-arm, at least one eccentrically disposed section formed on said work-table supporting shaft and on which said work-table is journaled, and manually actuated work-table supporting shaft turning connections operatively associated with said work-table supporting shaft for effecting limited turning of said shaft to move said work-table upwardly or downwardly relative to said frame-arm.

3. In a blind-stitch sewing machine, a main frame including a standard having an upper arm extending laterally therefrom and terminating in a forwardly ex-

tending frame-arm, and a base-arm section extending forwardly from said standard and cooperating with the latter to support the frame; a work-table movably supported on said base-arm and having a portion disposed below the level of the free end of said forwardly extending frame-arm; eccentric means located at the point of support of said work-table on said base-arm and providing a bearing support on which said work-table is journaled; and manually controlled connections operatively connected to said eccentric means for rotating the latter and thereby effecting a movement of said work-table relative to said base-arm.

4. In a blind-stitch sewing machine, a main frame including a standard having an upper arm extending laterally therefrom and terminating in a forwardly extending frame-arm, and a base-arm section extending forwardly from said standard and cooperating with the latter to support the frame; a work-table mounted on said base-arm and having a portion disposed below the level of the free end of said forwardly extending frame-arm; a work-table supporting shaft journaled in said base-arm and having formed thereon spaced eccentrically disposed portions on which said work-table is journaled; manually actuated work-table supporting shaft turning connections operatively associated with said work-table supporting shaft for effecting limited turning of said shaft thereby to regulate the normal working position of said work-table; and means for turning said work-table about the axis of the eccentrically disposed portions of said work-table supporting shaft to move said work-table toward and away from said frame-arm.

5. In a blind-stitch sewing machine; a main frame including an open sided standard having an upper arm extending laterally therefrom and terminating in a forwardly extending frame-arm, a base-arm section extending forwardly from said standard and cooperating with the latter to support the frame, and a cover-plate detachably secured to said standard to close its open side; a work-table section movably mounted on said base-arm and having a portion disposed at a level below the free end of said forwardly extending frame-arm; a work-table supporting shaft mounted in said work-table and journaled for limited turning movement on said base-arm and providing the support about which said work-table moves, said work-table supporting shaft having at least one eccentrically disposed portion on which one of said sections is journaled; and work-table supporting shaft turning connections operatively associated with said work-table supporting shaft for effecting limited turning of said shaft to move said work-table section upwardly or downwardly relative to said frame-arm, said work-table supporting shaft turning connections including a manually actuable member carried on said cover-plate and separably associated with the remaining shaft turning connections so that the cover-plate and the manually actuable member can be readily removed from said standard.

6. In a blind-stitch sewing machine, a main frame including a standard having an upper arm extending laterally therefrom and terminating in a forwardly extending frame-arm, and a base-arm section extending forwardly from said standard and cooperating with the latter to support the frame; a work-table section movably mounted on said base-arm and having a portion disposed at a level below the free end of said forwardly extending frame-arm; a work-table supporting shaft mounted in said work-table and journaled for limited turning movement on said base-arm and providing the support about which said work-table moves, said work-table supporting shaft having at least one eccentrically disposed portion with which one of said sections is in bearing contact; and work-table supporting shaft turning connections operatively associated with said work-table supporting shaft for effecting limited turning of said shaft to move said work-table section upwardly or downwardly relative to said frame-arm, said work-table supporting shaft turning connections including a rock-lever fixed on said work-table supporting

shaft, an adjusting lever disposed in said standard, a link connecting said adjusting lever to said rock-lever, and a manually actuatable member mounted for movement on said main frame and operatively connected to said adjusting lever whereby movement of said member will effect an adjustment of the working position of said work-table.

7. In a blind-stitch sewing machine, a main frame including a standard having an upper arm extending laterally therefrom and terminating in a forwardly extending frame-arm, and a base-arm extending forwardly from the lower portion of said standard; a supporting shaft journaled for turning movement in said base-arm, said shaft having at least one eccentrically disposed portion; a work-table journaled on said eccentrically disposed shaft-portion and having its free end disposed below the level of the free end of said frame-arm; a rock-arm secured to said supporting shaft; an adjusting lever pivotally mounted on said main frame and operatively connected to said rock-lever; and a thumb disk rotatably supported on said main-frame and connected to said adjusting lever.

8. In a blind-stitch sewing machine, a main frame including a hollow open-sided standard having an upper arm extending laterally therefrom and terminating in a forwardly extending frame-arm, a box-like base-arm extending forwardly from said standard and having an open top; stitch-forming and work-feeding mechanisms provided in said frame-arm; a work-table movably mounted on said base-arm and having its free end disposed below the free end of said frame-arm; a ridge-former carried by said work-table; ridge-former actuating mechanism disposed within said box-like base-arm and said hollow standard; and cover-plates closing the open top of said base-arm and the open side of said hollow standard, said cover-plates being constructed and arranged and of such size that when they are removed all the mechanism within the base-arm and standard is exposed for convenient adjustment or replacement.

9. In a blind-stitch sewing machine, a main frame including a standard having an upper arm extending laterally therefrom and terminating in a forwardly extending frame-arm, and a base-arm extending forwardly from said standard; a work-table movably mounted on said base-arm and having a portion disposed at a level below the free end of said forwardly extending frame-arm; adjustable stop means for positioning said work-table in its normal elevated position relative to said frame-arm; manually operable work-table lowering connections for moving said work-table away from said frame-arm; and yieldable connections for returning said work-table to its normal elevated position relative to said frame-arm, said yieldable connections including a spring and a linkage having a pivotally mounted element and a pair of links connected to said pivotally mounted element, said pivotally mounted element providing with said links a pair of lever-arms of which the ratio of the effective lengths thereof changes during the work-table lowering action of the manually operable work-table lowering connections in a manner to decrease the effort required to be expended by the operator in moving the work-table away from the frame-arm.

10. In a blind-stitch sewing machine, a main frame

including a standard having an upper arm extending laterally therefrom and terminating in a forwardly extending frame-arm, and a base arm extending forwardly from said standard; a work-table movably mounted on said base-arm and having a portion disposed at a level below the free end of said forwardly extending frame-arm; adjustable stop means for positioning said work-table in its normal elevated position relative to said frame-arm; manually operable work-table lowering connections for moving said work-table away from said frame-arm; and yieldable connections for returning said work-table to its normal elevated position relative to said frame-arm; said yieldable connections including a pivotally mounted element, a member connecting said pivotally mounted element to said work-table, a second member connected to said pivotally mounted element, and a spring connected at one end to said second member and at its other end to said main-frame.

11. In a blind-stitch sewing machine, a main frame including a standard having an upper arm extending laterally therefrom and terminating in a forwardly extending frame-arm, and a base-arm extending forwardly from said standard; a work-table movably mounted on said base-arm and having a portion disposed at a level below the free end of said forwardly extending frame-arm; adjustable stop means for positioning said work-table in its normal elevated position relative to said frame-arm; manually operable work-table lowering connections for moving said work-table away from said frame-arm; and yieldable connections for returning said work-table to its normal elevated position relative to said frame-arm; said yieldable connections including a pivotally mounted element, a member connecting said pivotally mounted element to said work-table, a second member connected to said pivotally mounted element, and a spring connected at one end to said second member and at its other end to said main-frame.

12. In a blind-stitch sewing machine, a main frame including a standard having an upper arm extending laterally therefrom and terminating in a forwardly extending frame-arm, and a base-arm extending forwardly from said standard; a work-table movably mounted on said base-arm and having a portion disposed at a level below the free end of said forwardly extending frame-arm; adjustable stop means for positioning said work-table in its normal elevated position relative to said frame-arm; manually operable work-table lowering connections for moving said work-table away from said frame-arm; and yieldable connections for returning said work-table to its normal elevated position relative to said frame-arm; said yieldable connections including a pivotally mounted element, a link connecting said pivotally mounted element to said work-table, a second link also connected to said pivotally mounted element, and a spring connecting said second link to said main frame.
